UNITED STATES PATENT OFFICE.

LOUIS M. GALATIUS AND NEWBURY R. MINOR, OF NEW YORK, N. Y.; SAID MINOR ASSIGNOR TO SAID GALATIUS.

EGG-BEATER.

SPECIFICATION forming part of Letters Patent No. 739,488, dated September 22, 1903.

Application filed June 16, 1900. Serial No. 20,568. (No model.)

To all whom it may concern:

Be it known that we, LOUIS M. GALATIUS and NEWBURY R. MINOR, citizens of the United States, residing at New York, in the county of New York and State of New York, have invented a new and useful Egg-Beater, of which the following is a specification:

This invention relates to egg-beaters.

The object of the invention is to provide a simple and thoroughly-efficient form of egg-beater, which, in addition to performing the functions specified, may also be employed after use as a beater to scrape the containing vessel, and thereby effect removal of all of the beaten egg.

With these and other objects in view, as will appear as the nature of the invention is better understood, the same consists in the novel construction and combination of parts of an egg-beater, as will be hereinafter fully described and claimed.

In the accompanying drawings, forming a part of this specification, and in which like numerals of reference indicate corresponding parts, there is illustrated one form of embodiment of the invention capable of carrying the same into practical operation, it being understood that the elements therein exhibited may be varied or changed as to shape, proportion, and exact manner of assemblage without departing from the spirit thereof.

In the drawings, Figure 1 is a view in perspective of the improved egg-beater. Fig. 2 is a view in transverse section. Fig. 3 is a view in end elevation, looking toward the end of the blade.

Referring to the drawings, 1 designates a flat flexible steel blade, similar to and of the thickness of an ordinary table-knife and provided with a rounded point, the edge 2 of the blade being sharpened and the back 3 being blunt, as usual, as clearly shown in Fig. 2.

The blade is fitted in a handle 4, provided with a metal ferrule 5 for the well-known purpose. The free extremity of the blade is provided with a plurality of openings 6, one of which is disposed within the rounded end of the blade, thereby to cause the device when in use to be thoroughly effective for beating the egg close to the bottom of the dish. By the manner of disposing the openings within the blade the greatest agitation, and thus mixing of the egg, will be effected, the flat surfaces between the openings operating in conjunction therewith to break up and cause rapid mixing of the yolk and white. As before stated, the blade is flexible and sharp on one edge, so that after an egg is beaten the device may be used to scrape the inside of the dish, and thus effect removal of all of the beaten egg.

While the device of this invention is exceedingly simple of construction, it will be found thoroughly efficient and durable in use for the purposes specified and may be manufactured and sold at a price readily to place it within the means of persons desiring such a utensil.

Having thus fully described our invention, what we claim as new, and desire to secure by Letters Patent, is—

A case-knife having a blade with a rounded end, said blade being provided with a plurality of transverse perforations one of which is located at the said rounded end of the blade, substantially as set forth.

In testimony that we claim the foregoing as our own we have hereto affixed our signatures in the presence of two witnesses.

LOUIS M. GALATIUS.
NEWBURY R. MINOR.
